(57) **CLAIM**

The ornamental design for a shear spring for a suspension, as shown and described.

DESCRIPTION

FIG. 1 is a bottom right front corner perspective view of a shear spring for a suspension having the inventive design; FIG. 2 is a bottom plan view of the shear spring for a suspension shown in FIG. 1;

FIG. 3 is a top plan view of the shear spring for a suspension shown in FIG. 1;

FIG. 4 is a left side elevation view of the shear spring for a suspension shown in FIG. 1;

FIG. 5 is a right side elevation view of the shear spring for a suspension shown in FIG. 1;

FIG. 6 is a front elevation view of the shear spring for a suspension shown in FIG. 1;

FIG. 7 is a rear elevation view of the shear spring for a suspension shown in FIG. 1;

FIG. 8 is a bottom right rear corner perspective view of the shear spring for a suspension shown in FIG. 1;

FIG. 9 is a top left front corner perspective view of the shear spring for a suspension shown in FIG. 1; and,

FIG. 10 is a top left rear corner perspective view of the shear spring for a suspension shown in FIG. 1.
